(57) **CLAIM**

The ornamental design for a lens for automobile lamp as shown and described.

DESCRIPTION

FIG. 1 is a front elevational view of a lens for automobile lamp, showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top front left perspective view thereof; and,

FIG. 8 is a rear side perspective view thereof.
